UNITED STATES PATENT OFFICE.

PAUL E. HITZIGRATH, OF ROCKVILLE CENTER, NEW YORK, ASSIGNOR TO S. GLEMBY'S SONS CO., INC., OF NEW YORK, N. Y., A CORPORATION OF NEW YORK.

HAIR NET.

Application filed March 10, 1928. Serial No. 224,151.

This invention relates to certain improvements in nets used for keeping women's hair in place, commonly known as hair nets.

These hair nets, as heretofore constructed, have been made by working human or other hair, or silks or similar material, into a comparatively large mesh of the desired size, then surrounding the same with a row of smaller sized mesh to draw the ends of the net closer together, the net in use being placed over the hair of the wearer by stretching the smaller sized mesh and opening the net thereby and drawing it over the coiffure to hold the same in position against blowing, etc.

It has been observed that the usual form of coiffure is almost always wavy and irregular in some degree, and for this reason the usual form of hair net, made as described above, will not perfectly adapt itself to the contour of the coiffure, not being elastic enough to do so, and is therefore capable of being readily detected.

My invention contemplates the construction of a hair net composed of strands of hair, silk or other suitable materials which are netted or woven in such a manner and the mesh of which is disposed in such a way, as to impart great elasticity to the net so that the net can adequately adapt itself to the hair of the coiffure.

Another object is to enable the net to be opened more fully than others as heretofore made, so that the same may be placed over the coiffure with the least difficulty and without disturbing the hair of the wearer, whereby the use of hair pins in securing the net to the hair is almost entirely eliminated.

A further object is to render the use of the net as an article of the coiffure less noticeable, by reason of the particular combination of meshes employed which permit of fashioning the same more closely conforming to the head of the wearer.

A still further object is to considerably increase the strength of the hair net by the provision of a greater number of strands within a given area than in nets as formerly made.

These and other features of the invention will be more particularly set forth in connection with the following specification and are illustrated in the accompanying drawings, in which

Fig. 1 is a side view of the net, pressed

closely together, as taken from its container, ready for opening to be placed over the coiffure of the wearer;

Fig. 2 is a fragmentary enlarged view of the net showing in detail the arrangement of its mesh.

Like characters of reference denote similar parts throughout the drawings and the following specification.

10 is a hair net, known in the trade as a self-conforming cap net, of substantially semi-spherical shape, composed of strands of hair 11. A central or uppermost portion 12 of the net is made of large sized mesh. Surrounding this large sized net work is a row 13 of slightly smaller sized mesh of hair. 14, 14^a and 14^b are three rows of the same size mesh, but less in size than mesh 13. 15 is a row of mesh surrounding row 14^b, and of a size still smaller than the mesh of rows 14, 14^a and 14^b. At the extreme end of the net surrounding row 15, are three rows of mesh, 16, 16^a and 16^b, all of the same size but still smaller than the mesh mentioned heretofore.

In knitting these nets, which is customarily done by hand, a central oblong section is first made up of the largest sized mesh 12, then the smaller sized meshes are knitted around it, gradually drawing the outer part together, to assume the shape outlined in Fig. 1.

By means of the gradual decrease in size of the mesh of the net to its open end, it is obvious that much greater elasticity is imparted to the net, so that the same will adjust itself to coiffures to a much greater degree than nets as commonly made. Moreover, the open end of the net, by virtue of its graduation of mesh, can be opened more widely, so that its open end will be of a diameter even larger than its central top portion 12 composed of the larger mesh, whereby the placing of the net over the coiffure may be effected without disturbing the same.

It will be understood that my invention is applicable to any kind of hair net and that various changes in the form, proportion and minor details of construction may be resorted to without departing from the principles or sacrificing any of the advantages of the invention, as defined in the appended claims.

So, for instance, while I have illustrated the hair net of substantially spherical form, the same may be of any desired and suitable

shape. Furthermore, while I have illustrated the mesh of the net made of single hair, the same may be of 2 or more strands, to impart greater strength to the net, if so desired. Moreover, while I have described the mesh of the net in rows of 3—1—3—1, respectively, each set of rows of gradually increasing size to the center, this is a preferred form only, and gradually increasing sizes of rows of mesh, in any other progressive order, will serve the purpose as well.

What I claim as new is:

1. A hair net of interwoven strands, having a central portion of relatively large mesh, surrounded by a single row of mesh, a plurality of rows of mesh, another single row, and another plurality of rows of relatively small mesh at its periphery, each single row and set of plurality of rows gradually decreasing in size of mesh to the size of the said relatively small mesh.

2. A hair net of interwoven strands, having a central portion of relatively large

mesh, surrounded by a single row of mesh, a set of three rows, another single row, and a peripheral portion of three rows of relatively small mesh, each set of rows and each single row gradually decreasing in size of mesh to the size of mesh in the said peripheral portion, substantially as described.

3. A hair net comprising a plurality of interwoven strands forming a central mesh portion, a single row of mesh surrounding said central portion, a group of rows of mesh, another single row surrounding said group of rows, and peripheral rows at the edge of the net, the meshes of said central portion, single rows, the group of rows and the peripheral rows all being of different sizes relative to each other, and the mesh of the rows of said group being of the same size.

In testimony whereof I have hereunto set my hand.

PAUL E. HITZIGRATH.
